UNITED STATES PATENT OFFICE.

MORRIS M. ALEXANDER, OF MARION, INDIANA.

DESIGN FOR A BADGE.

Application filed December 15, 1927. Serial No. 24,488. Term of patent 7 years.

To all whom it may concern:

Be it known that I, MORRIS M. ALEXANDER, a citizen of the United States, residing at Marion, in the county of Grant and State of Indiana, have invented a new, original, and ornamental Design for a Badge, of which the following is a specification, reference being had to the accompanying drawing, forming part thereof.

Fig. 1 is a face view of the badge, and Fig. 2 is an edge view thereof, showing my new design.

I claim:

The ornamental design for a badge, as shown.

MORRIS M. ALEXANDER.
